UNITED STATES PATENT OFFICE.

MERRITT L. HOTCHKISS, OF DERBY, CONNECTICUT.

DESIGN FOR A DRESS-STAY.

SPECIFICATION forming part of Design No. 26,879, dated April 13, 1897.

Application filed January 7, 1897. Serial No. 618,416. Term of patent 7 years.

To all whom it may concern:

Be it known that I, MERRITT L. HOTCHKISS, of Derby, in the county of New Haven and State of Connecticut, have invented a new Design for Dress-Stays; and I do hereby declare the following, when taken in connection with the accompanying drawing and the letters of reference marked thereon, to be a full, clear, and exact description of the same, and which o said drawing constitutes part of this specification, and represents a face view of a dress-stay embodying my design.

This invention relates to a design for a dress-stay; and it consists in the ornamentation and configuration, as hereinafter described, and shown in the accompanying illustration.

The design consists in the outer covering A for the stay, which is of open-mesh or net-like character and presents an ornamental covering, and a series of holes or openings a at each edge of the stay, said openings or meshes on the two opposite sides of the stay being symmetrically arranged and lying parallel one with the other, all as shown in the accompanying illustration.

I claim—

The design for a dress-stay as herein shown and described.

In testimony whereof I have signed this specification in the presence of two subscribing witnesses.

MERRITT L. HOTCHKISS.
